UNITED STATES PATENT OFFICE.

AUGUST WM. WIEGAND, OF SEDALIA, MISSOURI.

SAFETY APPLIANCE FOR LOCOMOTIVES.

1,271,642.

Specification of Letters Patent.

Patented July 9, 1918.

Application filed September 15, 1917. Serial No. 191,635.

To all whom it may concern:

Be it known that I, AUGUST W. WIEGAND, a citizen of the United States, residing at Sedalia, in the county of Pettis and State 5 of Missouri, have invented a new and useful Safety Appliance for Locomotives, of which the following is a specification.

The subject of this invention is a safety appliance for locomotives wherein a gravity 10 actuated valve operates to discharge steam in case of accident.

The main object of the invention is to provide a safety appliance which will allow the steam to escape rapidly from the boiler 15 when the locomotive upsets.

Another object is to produce a novel construction for a steam dome.

Another object is to provide novel means for normally closing the steam dome.

Another object is to provide auxiliary means whereby the engineer may release the steam when desired.

Still another object is to provide a simple and efficient device of this character.

With the foregoing and other objects in view which will appear as the description proceeds, the invention resides in the combination and arrangement of parts and in the details of construction hereinafter described 30 and claimed, it being understood that changes in the precise embodiment of the invention herein disclosed, can be made within the scope of what is claimed, without departing from the spirit of the invention.

A practical embodiment of the invention is shown in the accompanying drawings, wherein:

Figure 1 is a side elevation of an attachment constructed in accordance with the invention, the steam dome and a fragment of the boiler to which it is attached being in section.

Fig. 2 is a rear end elevation, the steam dome and locking mechanism removed.

Fig. 3 is a top plan view of the device attached to a boiler, a fragmentary portion of which is shown.

Fig. 4 is a front elevation of the device with a portion of the front standard broken 50 away.

Fig. 5 is a detail view showing segmental gears in revolved position.

Referring to the drawings by numerals of reference:

55 A boiler shell is indicated at 1 and rising from the boiler is a steam dome 2. The

steam dome 2, instead of being provided with the usual and ordinary dome cap, has its upper rim or periphery flared as at 3 to provide a suitable steam tight, wear compensating seat. While the rim is here shown flared, it is to be understood that any form of joint may be made that is deemed suitable for the purpose.

A bar 4 has its ends angled to seat within 60 the flared rim to which they are attached by rivets 4' or otherwise. Doors 5 formed with respective flanges 6 depending from their curved peripheries are provided with spaced, upstanding, apertured lugs 7, which 70 are adapted to contact and pivotally engage similar lugs 8 spaced along each edge of the bar 4. These pivotally connected lugs form hinges for the doors 5. Suitable packing 9 may be provided between the flared rim 3 75 and the flange 6.

A vertically disposed standard 10 is positioned adjacent the forward portion of the wall of the dome and has its angled foot 11 secured by rivets to the boiler shell 1. A 80 similar standard 10 is opposed to the first mentioned standard being arranged adjacent the rearward portion of the wall of the dome. Slots 12 extend longitudinally of the standards 10 for a portion of their length. 85

Alining apertures are formed in the upper ends of the standards 10 and within these apertures are journaled the ends of a rod or shaft 13. Rigidly secured on the shaft 13 within the standards 10 and in sliding contact therewith, are normally depending segmental gears 14. Nuts 15 may be threaded on the outwardly projecting ends of the shaft 13 if desired to form a supporting means for the upper end of the standards 10. 90

The segmental gears 14 mesh with small segmental gears 16. The segmental gear 16 adjacent the forward standard 10 is rigidly secured on a stub shaft 17 which projects 100 through the slot 12 in which it has a sliding fit. A nut 18 may be threaded on the outwardly projecting end of this stub shaft, or the shaft may be otherwise headed to retain the same in place in the slot. The inner end of the stub shaft 17 projects over the edge of and rests upon one of the lids or doors 5 which form the cap of the steam dome. 105

The other segmental gear 16, in this instance shown as the rearmost one, is rigidly mounted on a crank shaft 19 which pro-

jects through and is slidable in the slot 12 of the rear standard 10. The inner end of the shaft 19 projects over and rests on the other door 5. A nut 20 may be threaded 5 on the shaft 19 and contact the outer face of the standard 10 to properly retain the shaft within the slot. Segmental gears 16 normally rise from their shafts and mesh with the segmental gears 14 for the purpose 10 of holding the shafts 17 and 19 firmly pressed upon the doors or lids 5.

The angled end 21 of the crank shaft 19 has pivotal engagement with a piston rod 22, which rises from and reciprocates with 15 in a cylinder 23. The cylinder 23 is preferably vertically disposed and is secured to the boiler shell adjacent the rear standard 10. A steam pipe line 24 communicates with the lower end of the cylinder 23, and in this line 20 is interposed a throttle valve 25 arranged with its crank arm 26 horizontally disposed. A weight 27 is secured on the outer end of the crank arm 26 and contributes toward retaining the valve in a normally closed position. 25 A bell crank lever 28 engages the valve crank in the usual way and an operating rod 29 extends from the bell crank lever to the cab so that the throttle valve may be manually operated if desired.

30 In practice the device operates in the following manner: Stub shaft 17 and crank shaft 19 are held firmly upon the lids or doors 5 by the segmental gears 14 meshing with and pressing downwardly upon the 35 segmental gears 16. The throttle valve 25 is normally closed by the weight 27 and the pressure of the steam. Should the locomotive jump the track and upset, the weight 27 will no longer act to keep the valve 40 closed, but will act to open the valve. This will admit steam from the boiler through the pipe line 24 and to the lower end of cylinder 23. The steam in cylinder 23 will force the piston rod 22 outwardly which will 45 revolve crank shaft 19 and with it, the segmental gear 16 which is secured on that shaft. Revolution of the segmental gear 16 will revolve the segmental gears 14, and through them the forward segmental gear 50 16. Revolution of these gears will soon turn the gears out of contact and allow the stub shaft 17 and crank shaft 19 to slide upwardly in the slots 12 under the impulse of the steam in the dome which presses the 55 lids 5 outwardly. The steam dome being now wide open, steam rapidly rushes from the boiler and empties the same, the steam being dissipated in the air.

The same result may be obtained by actuating the operating rod 29. This is done 60 by the engineer when he sees that a collision

is inevitable. This allows the steam to rapidly escape and lessen the danger of occupants of the engine or train being scalded after the accident.

This device, when used on a steamship (where weight 27 will be omitted), will enable the fireman or engineer to release the pressure from the boiler when the ship is about to sink and thereby prevent a possible 70 explosion, caused by cold water coming in contact with the boilers.

Having thus described the invention, what is claimed as new and sought by Letters Patent is:

1. In a safety attachment for locomotives, the combination with a steam dome, of lids hinged to the dome, means for retaining the lids in normally closed position, and automatically controlled means for releasing the 80 retaining means to permit the lids to open.

2. In a safety attachment for locomotives, the combination with a steam dome, of lids hinged on the dome and forming a cap therefor, revoluble means for normally locking the lids in closed position, and automatically controlled means for revolving the locking means to release the lids.

3. In a safety attachment for locomotives, the combination with a steam dome, of lids hinged on the dome and forming a cap therefor, opposed standards secured adjacent the dome and rising thereabove, means journaled in the standards for normally retaining the lids in closed position, and fluid 95 operated means for actuating the retaining means to release the lids.

4. In a safety attachment for locomotives, the combination with a steam dome, of lids hinged to the dome and forming a cap therefor, opposed standards adjacent the dome and rising thereabove, lid contacting members slidably secured in the standards, means journaled in the standards binding the lid contacting member upon the lids, and means 100 for revolving the binding means to release the contacting members.

5. In a safety attachment for locomotives, the combination with a steam dome, of lids hinged to the dome, means for normally retaining the lids in closed position, fluid actuated means for operating the retaining means to release the lids, a source of fluid supply, and a gravity actuated valve for controlling the supply of fluid.

In testimony that I claim the foregoing as my own, I have hereto affixed my signature in the presence of two witnesses.

AUGUST WM. WIEGAND.
